UNITED STATES PATENT OFFICE.

FRED B. WELLS, OF RITTMAN, OHIO, ASSIGNOR TO THE OHIO BOXBOARD COMPANY,
OF CLEVELAND, OHIO, A CORPORATION OF OHIO.

PAPER STOCK DENSITY REGULATOR.

Application filed September 22, 1926. Serial No. 137,117.

In the manufacture of paper, and particularly in the manufacture of boxboard and similar paper-boards, the thickness and quality of same is dependent upon the density of the paper stock or pulp. This density varies relatively to the percentage of water present in the stock, and, obviously, in order to produce an even homogeneous web of paper or paper-board the density of the stock, and hence the percentage of water therein, must be maintained substantially constant throughout any given run of the paper making machine or mill.

Papermakers, and others skilled in the paper-making art, are conversant with the difficulties incident to controlling the density of the paper stock, occasioned by methods now commonly used for regulating the amount of water combined with the stock in the various stages of its treatment.

The object of this invention is to provide a method of and apparatus for regulating the density of the paper stock by automatically adding thereto water in sufficient quantities to produce a stock of such density as will form a web having a predetermined thickness and other desired characteristics.

This addition of water to the stock takes place after the stock has been treated by the Jordan engines and before it is introduced into the stuff chests, and, therefore, inasmuch as it is pumped direct from the stuff chests to the paper making machine, the proper density of the stock to produce a paper or board having the desired predetermined characteristics of weight and quality is assured.

The invention consists in a method of regulating the density of paper stock, which consists in adding to the fully treated or worked stock, water in quantities determined and controlled by the density of the stock itself; and in apparatus for carrying out this method which consists, broadly in a vessel interposed in the course of travel of the paper stock from the stock-working machinery to the paper-making machine, means being provided for feeding water to said vessel and thus to the paper stock, said means being operable in response to the relative density of the stock for controlling the feed of water to said vessel, as I will proceed now to explain and finally claim.

In the accompanying drawing illustrating the invention, the figure is a sectional eleva-

tion of the apparatus of my invention, showing a preferred location thereof relatively to other parts of the paper-making machinery.

The method of my invention consists in feeding to the paper stock, after it has been fully worked, water in quantities automatically regulated by the density of the stock itself, and a preferred embodiment of the apparatus for carrying out this method consists in a vessel 1, preferably in the form of a tank, open at its upper end, provided with a riser 2 having an adjustable extension sleeve or tube 3 which may be raised or lowered for a purpose hereinafter appearing, the riser and tube forming a compartment within the vessel.

The vessel 1 is connected through the riser 2 and tube 3 by means of a conduit 4 with a Jordan engine 5, whereby the riser 2 and tube 3 are fed and kept filled with fully worked paper stock. The stock as it overflows at the top of the tube 3 drops to the bottom of vessel 1 from which it is conducted by means of a pipe 6 to the stuff chests (not shown) from which latter it is pumped, in the usual manner, to the paper-making machine.

A pipe 7 extending into the vessel 1 leads to a suitable supply of water, and is provided with a valve 8 for controlling the flow of water therethrough to the vessel 1. This valve 8 has its stem 9 connected by means of a pivoted lever 10 with a rod 11 vertically slidable in guides 12 and provided with a float 13 normally supported by the column of paper stock in the riser 2 and tube 3. A weight 14 is slidably mounted upon the lever 10 for regulating the buoyancy of the float and hence the point of opening of valve 8 under the influence of the float as influenced by the density of the stock.

A further adjustment of the float may be obtained by means of the connection of the rod 11 with the lever 10, this connection comprising an adjustable collar 15 carrying trunnion pins 16 which engage slots 17 in the free end 18 of the lever 10.

In working the paper stock in the Jordan engine, the "freeness" or "slowness" of the stock depends upon the length of time allowed for the Jordan engine to work or cut it. Thus, if the stock is passed rapidly through the Jordan engine, a "free" or "longstock", such as is used to form a heavy sheet is produced, whereas, if the stock is held back in

the Jordan engine, a "slower" or "shorter stock", such as is used in forming a lighter sheet, is produced. It is for the purpose of regulating this action of the Jordan engine upon the stock that the adjustable sleeve is provided, it being evident that the higher the sleeve is set, the longer will the stock be retained in the Jordan engine and the "shorter" or "slower" will be the stock when it leaves

10 same.

When the sleeve is adjusted, the float 13 may be appropriately adjusted also, by means of rod 11 and adjustable collar 15, so that the float may bear a relatively normal buoyant 15 relation to the surface of the column of stock in the riser 2 and tube 3.

The operation of the apparatus is as follows:—The thickness and quality of the paper to be produced are determined, and the 20 tube or sleeve 3, collar 15 and weight 14 are adjusted to such positions that a paper stock of the "freeness" or "slowness" and density required to produce the paper having the characteristics determined will not lift the 25 float 13 and hence will not open the valve 8. Obviously, with this setting, if the stock coming from the Jordan engine and rising in tube 3 should become of a density greater than that desired, the float will be buoyed up by the 30 column of stock and will open the valve 8 sufficiently to feed water through pipe 7 in just the amount and at just the rate necessary to thin the stock to the required density.

Of course, care must be taken in operating 35 the beaters not to let the stock become too thin, for the reason that the device of the invention functions only when the stock is of too great density and requires the addition of water to thin it to the desired density.

40 The effect of the float 13 upon the valve 8 may be varied either by varying the height of the column of stock by adjustment of sleeve 3, by varying the setting of the collar 15 on rod 11, or by varying the position of the 45 weight 14 on lever 10; or by any or all of these means, whereby the times and extent of opening and closing of valve 8 and consequently of the volume and duration of water supply to the stock may be varied to suit the

conditions requisite to the production of 50 paper having the characteristics desired.

Various changes are contemplated as within the spirit of the invention and the scope of the following claims.

What I claim is:—

1. Apparatus for regulating the characteristics of paper stock, including a stock-working engine, a vessel connected with said engine and provided with a compartment into which the stock is fed from said engine, means 60 for varying the height of said compartment to vary the effective action of the engine upon the stock, and means for feeding water to the stock in response to its density, including a water supply provided with a valve, a float 65 buoyed by the stock in said compartment, and connections between said float and valve.

2. Apparatus for regulating the characteristics of paper stock, including a stock-working engine, a vessel connected with said engine and provided with a riser into which the stock is fed from said engine, a tube carried by said riser and vertically adjustable relatively to said engine to vary the effective action of the engine upon the stock, and means 70 for feeding water to the stock in response to its density, including a water supply provided with a valve, a float buoyed by the stock in said riser and tube, and connections between said float and valve.

3. Apparatus for regulating the characteristics of paper stock, including a stock-working engine, a vessel connected with said engine and provided with a riser into which the stock is fed from said engine, a tube carried by said riser and vertically adjustable relatively to said engine to vary the effective action of the engine upon the stock, and means for feeding water to the stock in response to its density, including a water supply 80 provided with a valve, a float buoyed by the stock in said riser and tube, connections between said float and valve, and means for varying the buoyancy of said float.

In testimony whereof I have hereunto set 95 my hand this 21st day of September A. D. 1926.

FRED B. WELLS.
